UNITED STATES PATENT OFFICE.

LOUIS F. STOECKER, OF PEORIA, ILLINOIS.

LID-HOLDER AND ADVERTISING DEVICE.

SPECIFICATION forming part of Letters Patent No. 635,904, dated October 31, 1899.

Application filed December 19, 1898. Serial No. 699,658. (No model.)

To all whom it may concern:

Be it known that I, LOUIS F. STOECKER, a citizen of the United States, residing at Peoria, in the county of Peoria and State of Illinois, have invented certain new and useful Improvements in Lid-Holders and Advertising Devices; and I do hereby declare that the following is a full, clear, and exact description of the invention, which will enable others skilled in the art to which it appertains to make and use the same.

This invention relates to a device for advertising purposes and for supporting open cigar-box lids for display.

As is well known, it is difficult to support cigar-box lids at an angle when on exhibit, so that the advertising matter thereon may be readily seen. Furthermore, it is difficult to arrange the lids or covers so that all will present the same appearance.

My object, therefore, is to provide a simple, easily-adjusted, and inexpensive attachment applicable to any form or size of box and which after being adjusted will hold the lid or cover firmly in any position. I also provide for the device so used an advertising-button which attracts the eye and is consequently a valuable addition to the device.

The drawings herewith show the form of the attachment and its application to a cigar-box.

Figure 1 is a perspective view of the device, showing a button upon its upper end. Fig. 2 is a perspective view of a portion of a cigar-box, showing the attachment in position. Fig. 3 is a rear view of the box, showing manner in which the wire holds the lid. Fig. 4 is a top view of the edge of the box-lid, wire, and button, showing manner of holding the lid.

My invention consists of a suitable length of spring-wire having at one end a semicircular bend *a*, sprung within the hollow button *b*. The wire extends outward or away from the button and is formed into a loop *c*, lying parallel with the plane of the button. Then, descending, the wire forms the bent body portion *d*. A coil *e* is formed at the lower

end of the said body portion, and the wire then rises to form the loop *f*, lying parallel with such portion, or substantially so. 50

In using the attachment the fork or loop *f* is made to straddle the rear edge of the box at one corner and is forced down to its place, as shown in Fig. 2. The said loop is formed somewhat narrower than the thickness of the 55 wood it straddles, so that when forced to its place it remains firmly fixed. The portion *d* is bent, as shown in Fig. 3, at *g*, and as the lid is raised the wire is forced outward away from the box; but when the lid reaches the 60 button the flexibility of the wire carries the loop *c* toward the lid and engages it, as shown in Fig. 4. Upon the button may be printed or stamped any advertising matter desired.

It is evident that the device shown and described may be used on other classes of goods and will be found convenient for a number of purposes. 65

I am aware that it is not new to provide a lid-holder; but I believe the particular form 70 and arrangement shown and described are new.

Having thus fully described my invention, I claim—

A lid-holder and advertising device consisting of a length of spring-wire having a display-button at its upper extremity, means for holding the button, a loop formed behind said button by recurving the wire upon itself, such loop adapted to clasp the box-lid, a long 80 curved portion terminating in a coil-spring, a loop extending therefrom formed by recurving the wire portion upon itself such loop being parallel with the said long curved portion and adapted to straddle the vertical wall of 85 the box, all being arranged substantially as shown and for the purposes specified.

In testimony whereof I affix my signature in presence of two witnesses.

LOUIS F. STOECKER.
